UNITED STATES PATENT OFFICE.

WILLIAM RICH, OF NEW YORK, N. Y.

MARINE FIRE-INDICATING SYSTEM AND EXTINGUISHER.

No. 892,088.

Specification of Letters Patent.

Patented June 30, 1908.

Application filed September 26, 1907. Serial No. 394,657.

To all whom it may concern:

Be it known that I, WILLIAM RICH, a citizen of the United States, residing at New York, in the county and State of New York, have invented certain new and useful Improvements in Marine Fire-Indicating Systems and Extinguishers, of which the following is a specification.

This invention relates to apparatus for indicating the presence of fire in the different holds, or bunkers of a ship, and to means combined therewith to extinguish any fire thus discovered, or which may be developing in any of the holds, or bunkers.

This invention is designed as an improvement on Patent Number 678,787, granted July 16, 1901, and owned by the Rich Marine Fire Indicating System Company.

The objects of this invention are: first, to provide a system of the character described so constructed that an extinguishing apparatus may be connected therewith, and, second, to provide an improved system of electrical control whereby the apparatus may be made more effective.

The invention is illustrated in the accompanying drawing in which—

Figure 1, is a diagrammatic view of a ship, and of my improved apparatus applied thereto; Fig. 2, is a perspective view of the station box,—the doors being open to show the apparatus connected therewith; Fig. 3, is an enlarged view of one of the pipe ends, and a sectional view of one of the flaring observation pipes; Fig. 4, is a diagrammatic view of the system of wiring; and Fig. 5, is a detail view of the clock contact mechanism.

In the drawing, like numerals of reference refer to the same parts in each of the views; and in practice I provide a station box 5, into which are led a plurality of pipes 6, from the several holds or bunkers, as indicated in dotted lines in Fig. 1. The pipes 6 extend up within the station box through a floor 7, which is close fitting about each pipe, so that when the door 8, is closed, and suction is applied to the pipes by the fan 9, air will be drawn through the pipes from the several holds or bunkers, and not from outside the station box.

On the top of each pipe 6, I mount an observation pipe 10, having a flaring end 11, so disposed that any smoke issuing therefrom may be readily observed through the glass panel 12, in the door 8, and it is obvious that

these pipes, and also the pipes 6, may be numbered, or marked in any suitable manner to indicate the particular hold or bunker to which it leads so that should any smoke issue from one of the pipes, the location of the fire 60 would be known instantly.

As shown in the drawing, the fan 9, is adapted to be run electrically every fifteen minutes, the current being turned on by means of a wheel 13, mounted on the hour 65 shaft of a clock 14, and carrying four pins 15, adapted to engage the contact brushes 16, for several minutes while passing the same thereby completing the circuit, and breaking the same when beyond the contact point, as 70 will be understood.

In operation, the station box is located at any convenient point on a ship; and when the clock 14 is in operation, the circuit will be closed every fifteen minutes, and the fan 9 75 will run a sufficient length of time to draw air from every hold or bunker of the ship. Mounted within the box is a light bulb 17, which is lighted when the current passes to operate the fan, and this not only calls attention to the fact that the fan is being operated; but will enable the officer to see the smoke should any be drawn through one of the pipes and the light not be sufficient to see it otherwise. A bell 18, is also provided to call the 80 attention of the officer to the operation of the fan. As shown in the diagrammatic view, Fig. 4, this bell may be cut out by a switch 19, should it be desired to eliminate the noise of the bell. 90

To provide ready means to extinguish the fire, should any develop in one, or more of the holds, or bunkers, I have so constructed the apparatus that any individual pipe 6, may be quickly connected with a steam pipe, 95 and steam may be passed through the pipe 6 to that particular hold or bunker to extinguish the fire. As the access of air to the holds or bunkers is usually very limited, I find it is usually a very easy matter to extinguish a fire that may develop, especially as a fire could not gain very much headway before being discovered. Even where air is admitted to the hold more or less freely, steam can be driven into the hold with such 105 force that almost any fire will be extinguished in the first stages. With this object in view, I have provided the top of each pipe 6, with a screw-threaded portion 20, and the observation tube, or pipe 10, is so constructed that 110

it will slip over this screw-threaded portion, and be held thereon by friction, so that when it is desired to connect the pipe with a steam pipe, this observation pipe may be removed without any loss of time, and the steam pipe may be connected.

In connecting the steam pipe, I prefer to use a flexible tube 21, to the end of which is secured a rigid tube 22, having an elbow 23, 10 and on the end I mount a union 24, with which connection may be made with the part 20, of the tube 6; and steam may be admitted by the valve 25, which is within easy reach of the operator.

15 It will thus be seen that I have provided ready means to extinguish any fire which may develop in any part of the ship, such means being within reach of the observation officer who is also possessed with means to 20 locate any fire within a few minutes at any time.

By providing the elbow 23, in the pipe 22, it is an easy matter to connect the union 24, with any of the pipes 6, even at the extreme 25 rear of the station box. It will also be observed that I may provide any number of these flexible connections and valves so that several of the pipes 6 may be connected with the steam pipe at the same time should it be 30 necessary to do so.

In improving the electrical system for operating the fan, I am able to make and break the current by means of the clock mechanism in a much more reliable manner; 35 and as the clock mechanism is mounted on the door 26, of the station box, the circuit can be made and broken without being observed from without, and the current need not pass through the clock mechanism, as 40 was the case where the hands carried the contact points.

In the diagrammatic view, Fig. 4, I have shown the system of wiring, from which it will be seen that the current may be cut off 45 entirely by the switch 27; and by the switch 28, the current can be turned on to operate the fan at any time at the will of the operator independently of the clock mechanism.

Having thus described my invention, what 50 I claim as new and desire to secure by Letters Patent of the United States is

1. In a marine fire indicating system, a station box, a plurality of pipes leading therefrom to the holds or bunkers of a ship, 55 means to draw air through said pipes into

said box, means to make visible any vapor issuing from any of said pipes and means to connect a steam pipe with any of said pipes.

2. In a marine fire indicating system, a station box, a plurality of pipes leading 60 thereinto, each of said pipes having a screw threaded end, an observation tube slidably mounted on the end of each pipe, and a flexible steam pipe adapted to connect with any of said pipes.

3. In a marine fire indicating system, a tube leading from the station box to the hold or bunker of a ship, said tube having a screw-threaded end, an observation tube slidably mounted on said screw-threaded end, said 70 observation tube having a flaring end, and a steam pipe adapted to be connected with said screw-threaded end when said observation tube is removed.

4. A marine fire indicating system comprising a station box, a plurality of pipes leading therefrom to the holds or bunkers of a ship, a fan mounted within said station box above said pipes, an electric motor to operate said fan, and a wheel mounted on a clock 80 works, said wheel being provided with posts adapted to contact with brushes to open and close the electric circuit periodically, and means to connect a steam pipe with any of said pipes.

5. The herein described fire indicating system and extinguisher comprising a station box, a plurality of pipes leading therefrom to the several holds or bunkers of a ship, said pipes having screw-threaded ends within 90 said box, an observation tube slidably mounted on each pipe, said observation tubes having flaring ends, an electrically operated fan mounted within said box above said tubes, a clock provided with a contact wheel on the 95 hour hand shaft adapted to periodically make and break the circuit, an electric bulb adapted to light when said fan is operated, an electric bell adapted to be thrown into said circuit, and a switch adapted to throw the current on said fan at the will of the operator, and means to connect a steam pipe with any of said pipes.

In testimony whereof I have signed my name to this specification in the presence of 101 two subscribing witnesses.

WILLIAM RICH.
